UNITED STATES PATENT OFFICE

172,528

LETTER RACK OR THE LIKE

Bernard Zipkin, Ossining, N. Y.

Application July 28, 1953, Serial No. 26,171

Term of patent 7 years

(Cl. D74—9)

To all whom it may concern:

Be it known that I, Bernard Zipkin, a citizen of the United States of America, residing at Ossining, in the county of Westchester and State of New York, have invented a new, original, and ornamental Design for a Letter Rack or the like, of which the following is a specification, reference being had to the accompanying drawing, forming a part thereof.

Fig. 1 is a front elevational view of a letter rack or the like, showing my new design.

Fig. 2 is a top plan view thereof.

I claim:

The ornamental design for a letter rack or the like, substantially as shown.
